UNITED STATES PATENT OFFICE.

WILLIAM H. PALMER, JR., OF NORWICH, ASSIGNOR TO PALMER BROTHERS,
OF MONTVILLE, CONNECTICUT.

MACHINERY FOR MAKING LAPS.

SPECIFICATION forming part of Letters Patent No. 404,106, dated May 28, 1889.

Application filed January 30, 1888. Serial No. 262,402. (No model.)

To all whom it may concern:

Be it known that I, WILLIAM H. PALMER, Jr., of Norwich, in the county of New London and State of Connecticut, have invented 5
5 a new and useful Improvement in Machinery for Making Laps, of which the following is a specification.

My invention relates to carding machinery for producing a lap or bat of carded material, as either wool or cotton, in which a number or series of cards arranged side by side deliver their fleeces upon a traveling apron mounted on apron-rollers in an apron-carrying frame, to which a traverse motion is 15 imparted in a direction transverse to the progressive travel of the apron. By such an arrangement of parts the fleeces from the said cards are laid across the apron in folds overlapping each other and extending from side 20 to side of the bat or lap, and the width of the bat or lap is fixed and determined by the length of traverse motion given the apron-carrying frame.

In carrying out my invention I usually employ 25 two series of cards arranged with the cards of one series facing the cards of the other series, and by suitable delivery apparatus—such as two delivery-boards arranged so that one terminates and delivers opposite 30 the face of the other—I combine the fleeces from two opposite cards before they are delivered onto the apron.

In carding machinery of the kind above described the thickness of the bat or lap produced may be varied by varying the speed of progressive travel imparted to the receiving-apron, the speed of delivery of the fleeces from the several cards remaining uniform, and the finished bat or lap is wound upon a 40 take-up beam or roller at the end of the apron-carrying frame.

Important objects of my invention are to secure a compact arrangement of the cards upon elevated supports, beneath which the 45 apron-carrying frame moves in its traverse motion; also, to provide for combining the fleeces from two oppositely-arranged cards before delivery to the apron; also, to provide a simple mechanism for traversing the apron- 50 carrying frame, and which is adjustable to vary the length of the traverse movement;

also, to provide for imparting the progressive travel to the apron during its traversing movement, and for varying the speed of such progressive travel during the operation of the 55 machinery, to secure the exact thickness and weight of the finished lap desired; also, to provide for imparting a uniform surface velocity to the take-up roller or beam notwithstanding its increasing size as the lap or bat is 60 taken up and wound or rolled upon it, and to provide for at once and automatically bringing an empty take-up roll or beam into receiving position at the same time that a filled take-up roll or beam is removed from the machine. 65

My invention consists in novel combinations of parts, hereinafter described, and pointed out in the claims, whereby the desired results are secured. 70

In the accompanying drawings, Figure 1 is an end view of machinery embodying my invention and comprising two series of cards facing each other, the apron-carrying frame only being in section. Fig. 2 is a longitudinal section on the plane of the dotted line x x , Fig. 1. Fig. 3 is a plan of the supports for the cards and the receiving-apron and its frame, the cards being omitted. Fig. 4 is a sectional view showing portions of the receiving-apron, its frame, the supporting and driving rollers, and the bearings for the take-up roller or beam, and the card-supports and traversing mechanism for the apron-carrying frame. Fig. 5 is a sectional view on the plane 85 of the dotted line y y , Fig. 4; and Fig. 6 is a broken side view of the mangle-rack and pinion for traversing the apron-carrying frame. Figs. 4, 5, and 6 are upon a larger scale than the other figures, and similar letters of reference designate corresponding parts in all the figures. 90

A designates cards or carding-machines of the ordinary kind, comprising a cylinder and workers, and also each having a doffer-cylinder, a . In the illustrated example of my invention the cards are arranged in two series, those in each series being side by side, and the cards of one series facing those of the other series, as shown in Fig. 1. I have here 100 shown but two cards in each series; but usually there will be four or more, the ma-

chine being proportionately longer. Along the cards of each series extends a shaft, A', and the two shafts are connected by a belt, as hereinafter described. Each card A will 5 be driven by a belt, a', as is usual, and as shown in Fig. 1, and in addition the only main belt necessary for imparting motion to the machinery from an outside source is a belt, a², running upon a pulley, a³, on one of 10 the shafts A'.

The cards A are supported in an elevated position by timbers or other girders, B, which afford below them a clear space for a receiving-apron, C, which is arranged in an apron-carrying frame, C', and which receives the fleeces from the several cards of both series. This apron C and frame C', together with their accompanying mechanism are shown in side and plan view in Figs. 2 and 3 and in 15 20 detail in Figs. 4 and 5.

The apron C may be made of two endless chains or bands, c, arranged parallel with each other and at a suitable distance apart, and slats or bars c', of wood, extend between and 25 are secured to the chains or bands.

At or near opposite ends of the frame C', and also intermediate of its length, are supporting-wheels c², running upon track-rails c³, and which provide for the easy traverse of 30 the frame in a direction transverse to the direction of progressive travel of the apron C.

Near opposite ends of the frame C' are cross-shafts C² C³, having upon them chain-wheels c⁴, which engage and support the chains 35 c of the apron C, and these shafts, with their wheels, may be considered as apron-supporting rollers. Upon the shaft C² is a worm-wheel, c⁵, with which engages a worm, c⁶, upon a short shaft, c⁷, and by motion imparted to 40 the short shaft c⁷, as hereinafter described, the apron roller or shaft C² is driven and the apron moved in the direction of the arrows thereon. Between the apron-rollers C² C³ the straight direct and return portions of the apron 45 C may be supported by bearers c⁸ or rollers c⁹, both of which forms of support are shown in Fig. 4, and on which the chains c travel along.

In addition to the progressive travel of the 50 apron C the frame C', and therefore the apron, must have a traverse motion in a direction transverse to the length of the apron and along the rails c³ beneath the girder-supports B. I have shown in Figs. 1, 3, 4, and 6 one form of 55 mechanism which may advantageously be employed for the purpose. Extending transversely across the frame C' is a mangle-rack, D, which has feet or legs d at opposite ends, whereby it is supported on the sides of the 60 frame C', and a mangle-pinion, E, upon a short shaft, e, and engaging therewith. The rack D comprises straight upper and lower rack portions and a pinion or shaft-guiding rib, d', and at the ends are portions D', made 65 separate from the main portion of the rack and adjustable to lengthen or shorten the rack, and thereby to vary the length of trav-

erse of the apron-frame C'. The pinion-shaft e is supported by a swinging arm e', pivoted at e² to one of the supporting-girders B, and motion is imparted to the shaft e by suitable gearing, such as a chain, e³, passing around wheels e⁴ e⁵ on the shaft A' and the shaft e, and over suitably-arranged deflecting-wheels e⁶ e⁷. 70 75

The adjustable end portions, D', of the mangle-rack also comprise portions d² of the guiding-rib d' for the pinion-shaft e, and are each secured in position by a pin, d³, which may be inserted in one of several holes, d⁴, provided for it, according to the degree of adjustment of the end portion, D'. The rack portions of the end portions, D', and also the rib portions d² thereof, lap upon the straight upper and lower rack portions and the rib d' 80 85 of the main rack D, and thus afford a continuity of the lines of teeth for engagement of the pinion E and a continuous bearing or guide for the pinion-shaft e, and as the length of the folds in which the fleeces from the cards A are delivered on the apron C is fixed by the length of the traverse movement it will be understood that the width of the finished lap or bat is varied by shifting the end portions, D', of the rack D, and thus increasing or reducing the length of said rack and the length 90 95 of traverse movement.

I will now describe how the short shaft c⁷ may be driven to impart a continuous progressive travel or movement to the apron during its traverse movement. 100

Upon the short shaft c⁷ is a loose pulley, f, and upon the opposite side of the apron-frame C' is a corresponding short shaft, f', carrying a pulley, f². Upon the shafts A' 105 are pulleys f³, and upon the supporting-girder B are idler-pulleys f⁴. The pulleys f f² f³ f⁴ are all in the same vertical plane, and a driving-belt, F, embraces the pulleys f³, passes down between and over the idler-pulleys f⁴, and embraces the loose pulley f and the pulley f². The traverse motion of the frame C' carries the pulleys f f² to and fro beneath the idler-pulleys f⁴; but as the pulleys f f² always remain the same distance 110 115 apart the belt F of fixed length always remains taut and properly drives the pulleys f f².

To provide for varying the speed imparted to the shaft c⁷ and through it to the apron C, 120 I fix upon the shafts f' c⁷ reversed cone-pulleys f⁵, which are connected by a belt, f⁶, as shown best in Fig. 3. The pulley f, being loose on the shaft c⁷, may rotate with the uniform speed at which the belt F is driven; but between the shafts f' c⁷ the speed is varied 125 by shifting the belt f⁶, and consequently any desired speed is given the shaft c⁷. If the finished lap or bat is too light, the belt f⁶ is shifted to reduce the speed of the shaft c⁷, 130 and if too heavy the belt is shifted to increase the speed of said shaft c⁷.

The lap or bat carried forward by the apron C is wound upon a take-up roller or beam,

G, as shown in Fig. 2, and in this example of my invention this take-up roller is at the end of the apron-frame C' opposite the driving mechanism just described for the apron. As 5 the take-up roll or beam G increases in size as the lap is wound upon it, it must be driven at a uniform surface velocity and not a uniform number of revolutions per minute.

At the delivery end of the apron-frame C' 10 are journaled two supporting drums or rollers, G', which have the same surface velocity as the apron and are driven as best shown in Fig. 2, but also in Fig. 4. On the shafts of the drums or rollers G' are wheels g, geared 15 together by an intermediate pinion, g', and through wheels g² g³, the former on the shaft C³ and the latter an idler-pinion engaging one of the wheels g, the rollers or drums G' are driven from the shaft C³ of the apron- 20 roller.

The take-up roller G is journaled between and rests upon the supporting drums or rollers G'. Its journals are fitted to slotted bearings, wherein they may rise as the take-up 25 roller increases in size. The bearings are formed by fixed brackets H, having slots h, and movable brackets H', pivoted concentrically with the pinion g' at h', and having open-topped slots h², which form continuations of 30 the slots h. When an empty take-up roller is put in the machine its journals rest in the slots h; but as it becomes filled up and larger by the lap winding upon it its journals rise into the slots h², its surface all the while resting 35 upon the rollers or drums G' and the take-up roller being rotated at a uniform surface speed by frictional contact with said rollers or drums. When the take-up roller G is full, the brackets H' are tilted forward by hand, 40 and as they bring the slots h² to a horizontal position the filled take-up roller G rolls out of them and upon a truck for receiving it.

By a very simple construction I provide for bringing an empty take-up roller into receiving 45 position automatically at the same time that the filled take-up roller is removed. The pivoted brackets have rearwardly-extending arms H² provided with inwardly-projecting flanges h³ or rests, whereon the journals of 50 the empty roller are supported, as shown in Fig. 4, and which are turned up at the back ends to form stops h⁴ to prevent the take-up roller from rolling off them. When the brackets H' are tilted forward to take out the filled 55 take-up roller, the empty roller rolls forward and drops into the empty slots h and into position on the surfaces of the supporting and driving drums or rollers G'. The attendant has then but to wrap the severed end of the 60 lap around the empty roller G to start the winding up of the lap or bat upon it, and this operation continues until the roller G is full.

In order to produce a lap or bat of even and full thickness even at the opposite edges I 65 prefer to combine by a suitable delivery the fleeces delivered from the two cards A, which

are opposite each other. The simple form of delivery apparatus here shown consists of two boards, I I', inclined in opposite directions, as shown in Fig. 1. The board I' is shorter 70 than the board I and terminates opposite the face of the latter, so that the fleece sliding down the board I' is delivered directly upon the fleece on the board I, and both slide down the lower portion of the board I together and 75 are delivered as one fleece upon the apron C.

The two series of cards A may be arranged very closely together, as shown, and as space is provided beneath the cards for the traversing apron-frame C' a very compact arrangement of a number of cards and their receiving-apron is obtained.

What I claim as my invention, and desire to secure by Letters Patent, is—

1. The combination, with two series of cards 85 arranged side by side and the two series facing each other, of an apron having a progressive travel past the cards, and also having a reciprocating traverse in a direction transverse to its progressive travel, and mechanism, substantially such as described, for imparting the progressive and traverse movements to the apron, substantially as herein described.

2. The combination, with a series of cards 95 arranged side by side and an elevated support for the cards, of an apron having a progressive travel past the series of cards, and also having a reciprocating traverse in a direction transverse to its progressive travel and 100 beneath the elevated support, and mechanism, substantially such as described, for imparting the progressive and traverse movements to the apron, substantially as herein described.

3. The combination, with two series of cards, those of each series being arranged side by side and facing those of the other series, of delivery apparatus whereby the fleeces from two opposite cards are combined, an apron 110 having a progressive travel past the cards, and also having a reciprocating traverse in a direction transverse to its progressive movement, and mechanism, substantially such as described, for imparting to the apron both its 115 progressive and traverse movements, substantially as herein described.

4. The combination, with two series of cards, those of each series being arranged side by side and facing those of the other series, of 120 an apron having a progressive movement past the cards, and having also a traverse movement in a direction transverse to its progressive movement, delivery-boards extending downward from opposite cards and one delivering against the other, whereby the fleeces from the two cards are combined before being delivered to the apron, and mechanism, substantially such as described, for imparting both the progressive and traverse motion to the apron, substantially as herein described.

5. The combination, with a series of cards arranged side by side, of an apron-carrying frame and an apron having a progressive movement therein past the series of cards, a 5 mangle-rack and pinion-gearing for reciprocating the said frame in a direction transverse to the progressive movement of the apron, and mechanism, substantially such as described, for imparting the progressive movement to the apron in said frame, substantially as herein described.

6. The combination, with a series of cards arranged side by side, of an apron-carrying frame having rollers and an endless apron 15 passing around said rollers, a mangle-rack upon the frame, having adjustable portions at its end, and the pinion-guide, extensible, and having means for holding the extensible end portions in fixed position after adjustment, a mangle-pinion engaging said rack, and mechanism, substantially as described, for operating it, and mechanism for operating the apron-rollers to give the apron a progressive travel, substantially as herein set forth.

25 7. The combination, with a series of cards arranged side by side, an apron - carrying frame having rollers, and an apron having a progressive travel around said rollers in a direction past the series of cards, of mechanism, 30 substantially such as described, for imparting a reciprocating traverse motion to the frame in a direction tranverse to the progressive travel of the apron and for operating the apron roller or rollers, a pair of supporting- 35 rollers beyond the apron in said frame and serving to support a take-up roller, and mechanism, substantially such as described, for driving the supporting-rollers both in the same

direction, so that they will rotate the take-up roller placed upon them, substantially as herein set forth. 40

8. The combination, with a series of cards arranged side by side and an apron-carrying frame having rollers supporting a traveling apron for movement in a direction past 45 the cards, of supporting-rollers beyond the apron in said frame for supporting upon them a take-up roll, mechanism, substantially such as described, for imparting a progressive travel to the apron and a reciprocating traverse 50 motion to the frame and for rotating the supporting-rollers both in the same direction, the fixed slotted bearings H for the take-up roll, and the pivoted slotted bearings H', forming continuations of the slots in the fixed 55 bearings, and having brackets H² for the support of a fresh roller, which will roll into the slots of the fixed bearings when the pivoted slotted brackets are swung on their fulcrums, substantially as herein set forth. 60

9. The combination, with a series of cards arranged side by side and an apron-carrying frame having rollers and an endless apron passing around said rollers, a mangle-rack upon the frame having adjustable portions at 65 its ends, a pinion-guide made extensible, a pin for holding the extensible end portion in fixed position after adjustment, a mangle-pin engaging said rack, and mechanism, substantially such as described, for operating said 70 pinion and the apron-rollers, substantially as specified.

WM. H. PALMER, JR.
